Des. 32

Ezra Ripley assignor of Dagger, Treadwell & Perry,
Troy, New York.

Letters Patent (Design) No. 32 dated 14th July 1845.

The schedule referred to in these Letters Patent and

making part of the same.

To all whom it may concern: Be it known that I, Ezra Ripley of Troy in the County of Rensselaer and State of New York, have invented or produced new designs or figures to be cast upon stone plates, or to be used in forming the moulds for casting stone plates, and I do hereby declare that the annexed drawing exhibits a full and exact representation of said designs or figures as they appear upon a stone, the plates of which are cast in a mould formed from patterns upon which the said designs have been carved or otherwise formed.

What I claim as my invention and desire to secure by letters patent is the conformation and arrangement of figures of fruit & foliage as represented in the annexed drawing.

I do not claim as my invention the form or arrangement of the stone, but only the conformation & arrangement of the figures aforesaid
